UNITED STATES PATENT OFFICE.

ANTON VAN VEEN, OF WEST HARTFORD, CONNECTICUT, ASSIGNOR TO THE FULLER BRUSH COMPANY, OF HARTFORD, CONNECTICUT, A CORPORATION OF CONNECTICUT.

MACHINE FOR MAKING BRUSHES.

Application filed January 6, 1925. Serial No. 827.

My invention relates to the class of devices employed in the making of brushes more especially in which the brush material is secured to a twisted wire core, and an object of the invention, among others, is the production of a machine that shall be simple in construction and particularly rapid and otherwise efficient in operation.

One form of machine embodying my invention and in the construction and use of which the objects herein set out, as well as others, may be attained is illustrated in the accompanying drawings, in which—

Figure 1 is a view in side elevation of a machine embodying my invention.

Figure 2 is a top view of my improved machine.

In the accompanying drawings the numeral 5 indicates the bed of my improved machine that may be supported in any desired manner, as by legs 6, this machine, in the specific form herein illustrated and described, embodying mechanism for trimming the brush material to a round form in cross section, together with mechanism for afterwards bending the trimmed structures into a form preparatory to receiving the handles, the machine also embodying means for feeding the brushes to the trimming mechanism and, therefrom to the bending mechanism, said trimming and bending mechanisms being connected to operate in unison so that brush structures are simultaneously delivered from the trimming mechanism, supplied to the bending mechanism and delivered from the bending mechanism, whereby the supply of said structures to the bending mechanism is maintained sufficient to supply the demand of said bending mechanism and do no break the sequence of bending operations.

The bending and trimming mechanisms are mounted upon the bed 5, the latter comprising standards 7 secured to the bed and rising therefrom at opposite sides thereof and supporting the lower ends of side parts 8 of a trimmer feed, there being two of these side parts each having a slot 9 within which the twisted wire cores 10 of brush structures 11 are located and along which they travel to the trimming mechanism, the side parts being inclined sufficiently to cause the brushes to gravitate toward said trimming mechanism. The trimmer comprises a carrier composed of two end discs 12 each having

notches 13 to receive the ends of the brush cores, said carrier being mounted in suitable bearings rotatably supported by the standards 7. A ratchet wheel 14 is secured to the shaft of the carrier, the notches of said wheel being engaged by a pawl 15 on a rocking pawl support 16 loosely mounted on the shaft of the carrier, one end of the support being connected by a rod 17 with a pawl actuating lever 18 pivotally mounted on a bracket 19 rising from the bed 5. One end of this lever is located in the path of movement of the end of a bending slide 20 comprising a portion of the bending mechanism, said slide being operated for a complete reciprocating movement to and fro at each bending operation.

A trimmer comprising trimming knives 21 supported by a shaft 22 mounted in bearings on standards 23 located on the bed 5 is positioned underneath the path of travel of the brush structures 11 as they are moved forward by the carrier hereinbefore referred to, guides 24 being employed for directing movement of the brush structures and for preventing the latter from falling out of the notches in the carrier. These structures are so located and supported by the guides and carrier that they will freely rotate, and as the rapidly rotating knives 21 come in contact with the peripheries of the brush structures the latter are caused to rapidly rotate with a result that a trimming operation is effected in a rapid and expeditious manner, the brush structures being trimmed smooth and true to the form desired, this depending upon the shape of the knives 21. The brush structures herein shown are of cylindrical shape, but any other desired shape, as conical or otherwise, may be imparted to said structures.

As these brush structures pass from the action of the trimming mechanism they are moved along a chute or feed device comprising side parts 25 preferably of A-shape, the brush structures traveling up one branch of the chute, this travel being caused by said structures being pushed along by the brush structures in the rear that are delivered from the carrier. After passing the bend in the chute the brushes travel by gravity down the other branch of said chute, their delivery to the bending mechanism being regulated by detents 26 located in the path of movement of cams 27 on bending arms 28, 110

which arms have an oscillatory movement during the bending operation.

Briefly described the ends of the brush structures are delivered by the chute comprising the side parts 25 in the path of movement of clamping jaws 29 located on the arms 28 and by which they are grasped, there being two of said arms and by the operation of which said structures are bent 10 around former pins 30, and after being bent they are ejected by an ejector 31 pivotally mounted at one end between brackets 32 secured to a table 33. The bending slide 20 has a reciprocating movement imparted to it by means of a bending crank rod 34, one end of which is pivoted to a crank disc secured to a shaft 35 mounted in bearings in a housing 36, said shaft being connected as by bevel gears with a driving shaft 37 20 mounted on the housing 36 and having a driving pulley 38 secured thereto. The arms 28 are oscillated as by means of a rack 39 secured to the slide 20 and with which rack the rod 34 is directly connected, the teeth of 25 said rack meshing with pinions 40 secured to the lower ends of shafts to the upper ends of which the bending arms 28 are attached.

The description thus far given is sufficient for the purpose of my invention embodied 30 herein, the bending mechanism herein illustrated, as to the details thereof, being shown and described in my copending application of Serial Number 756,861, filed December 19, 1924, to which reference is hereby made for 35 a more complete understanding of the details of construction of said bending mechanism, if such shall be desired.

It will be noted that the runway along 40 which the brushes pass to the trimming mechanism and therefrom to the bending mechanism comprises runners on each side of the machine, said runway being spaced apart intermediate its ends to provide a space for the carrier of the trimming mechanism, said carrier operating to convey brush structures across the space between the parts of the runway.

In accordance with the provisions of the 50 patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim—

1. A runway for brush structures having 60 flexible cores with bristles projecting therefrom, said runway constituting a guide comprising spaced runners, means at one end of the guide for performing a looping operation upon said structures, means in the space 65 between said runners for performing a trim-

ming operation upon said structures, and means for effecting a step-by-step movement of said structures in time with the performed operation at the end of the runway.

2. A runway for brush structures having 70 flexible cores with bristles projecting therefrom, said runway constituting a guide comprising spaced runners, means at one end of the guide for performing a looping operation upon said structures, means in the space 75 between said runners for performing a trimming operation upon said structures, and means connected with the mechanism for performing the trimming for effecting a step-by-step movement of said structures in 80 time with the performed operations at the ends of the runway.

3. A runway for brush structures having 85 flexible cores with bristles projecting therefrom, said runway constituting a guide comprising spaced runners, means in the space 90 between said runners intermediate the ends of said runway for performing a trimming operation upon said structures, means at one 95 end of the runway for performing a looping operation upon said structures, and feeding means associated with the mechanism for performing the trimming operation to effect a step-by-step movement of the brush structures, said feeding means being operated by the means for performing the looping operation to effect said step-by-step movement in time with the performed operations.

4. A runway for brush structures having 100 flexible cores with bristles projecting therefrom, said runway constituting a guide comprising spaced runners, mechanism in the space between said runners intermediate the 105 ends of said runway for performing a trimming operation upon said structures, means at the end of the runway for performing a looping operation upon said structures, the 110 runners between said mechanisms being of inverted V-shape and up one branch of which structures travel from one mechanism and down the other branch of which said structures travel to the other mechanism, and means for effecting a step-by-step movement of said structures along said inverted V-shaped runners in time with the performed 115 operations.

5. A brush forming machine comprising a 120 mechanism for performing a trimming operation upon brush structures having flexible cores with bristles projecting therefrom, an intermittently operated feed device for the brush structures for feeding them periodically to said trimming mechanism, means for looping the brush structures during inactivity of the feed device, means for delivering brush structures from the trimming mechanism to the looping mechanism, and means for imparting a one step movement to the feed device during each operation of the looping mechanism.

6. A brush forming machine comprising a mechanism for performing a trimming operation upon brush structures having flexible cores with bristles projecting therefrom, 5 an intermittently operated feed device for the brush structures for feeding them periodically to said trimming mechanism, means for looping said brush structures during inactivity of the feed device, means for delivering brush structures from the trimming mechanism to the looping mechanism, and operative connections between the feed device and looping mechanism for imparting a one step movement to the feed device during 10 each operation of the looping mechanism.

7. A brush forming machine comprising a mechanism for performing a trimming operation upon brush structures having flexible cores with bristles projecting therefrom, a 20 second mechanism for performing a looping operation upon said brush structures during a pause in the movement of the brush structures, and a feed device for conducting brush

structures from the trimming mechanism to the looping mechanism with a step-by-step movement, said feed device being operated to deliver a brush structure to the looping mechanism each time a brush structure is delivered therefrom. 25

8. A brush forming machine comprising a mechanism for performing a trimming operation upon brush structures having flexible cores with bristles projecting therefrom, a second mechanism for performing a looping operation upon said brush structures during 30 a pause in the movement thereof, and a feed device for conducting structures from the trimming mechanism to the looping mechanism with a step-by-step movement, said feed device being connected with the looping 35 mechanism for operation thereby and said feed device being operated to deliver a brush structure to the looping mechanism each time a brush structure is delivered therefrom. 40

ANTON VAN VEEN.
